CLAIM

The ornamental design for an ATV trailer, as illustrated and described.

DESCRIPTION

FIG. 1 is a perspective view of an ATV trailer according to the preferred embodiment of the present invention; FIG. 2 is a rear view of the ATV trailer illustrated in FIG. 1; FIG. 3 is a front view of the ATV trailer illustrated in FIG. 1;

FIG. 4 is a top plan view of the ATV trailer illustrated in FIG. 1;

FIG. 5 is a left side view of the ATV trailer illustrated in FIG. 1, the right side view being substantially similar; and, FIG. 6 is a bottom view of the ATV trailer illustrated in FIG. 1.

The broken lines shown in the FIGS. 1, 4, 5, and 6 drawing views are for illustrative purposes only and forming no part of the claimed design.
